UNITED STATES PATENT OFFICE.

HARRY P. DAVIS, OF PITTSBURG, PENNSYLVANIA, ASSIGNOR TO THE
WESTINGHOUSE ELECTRIC AND MANUFACTURING COMPANY, OF
SAME PLACE.

SUPPORTING MEANS FOR ELECTRIC-RAILWAY SUPPLY-CONDUCTORS.

SPECIFICATION forming part of Letters Patent No. 580,381, dated April 13, 1897.

Original application filed June 10, 1896, Serial No. 595,003. Divided and this application filed September 17, 1896. Serial No. 606,148. (No model.)

To all whom it may concern:

Be it known that I, HARRY P. DAVIS, a citizen of the United States, residing in Pittsburgh, in the county of Allegheny and State 5 of Pennsylvania, have invented a new and useful Improvement in Supporting Means for Electric-Railway Supply-Conductors, (Case No. 713,) of which the following is a specification, this application being a division of 10 my application filed June 10, 1896, Serial No. 595,003.

My invention relates to supporting means for overhead supply-conductors for electric railways; and it has for its object to provide 15 a simple, inexpensive, and effective device for supporting such conductors either from one or both sides of the track in such manner as to avoid any displacement of the same with reference to the track-rails as well as 20 any danger of interference with current-collecting devices.

In devices heretofore employed for making the connection between the pull-off wires and the overhead conductors for electric railways, the device itself has either extended below 25 the supply-conductor in order that the strain upon the conductor might be applied in the same horizontal plane with it, or the pull-off wires have been attached to the supporting 30 device above the horizontal plane of the conductor. The first-named construction is practically useful where grooved trolley-wheels are employed as current-collecting devices, and the last-named construction is practically 35 useful in straight-line work or in connection with laterally-extending collecting devices. Such a construction is not suitable for curves, however, particularly in cases where the pull-off wires are located at one 40 side of the track only, for the reason that the proper location of the conductor with reference to the track-rails is not maintained. The other construction, in which the supporting devices extend below the horizontal plane 45 of the supply-conductor, obviously precludes the use of a laterally-extending contact device.

My present invention is suitable for use on either straight-line work or at curves and in

connection with any practical form of current-collector.

In the accompanying drawings, Figures 1, 2, and 3 are respectively a side elevation, a plan, and an end elevation of my supporting device.

Referring now to the details of construction, 1 is a supporting piece or bar having a curved lower edge and provided along its upper edge with a longitudinal groove 2 for the reception of a supply-conductor, this being 60 either clamped around or soldered to the conductor in order to securely support the same. This piece 1 is provided substantially midway of its ends with either one or two laterally-projecting ears 3, preferably integral 65 therewith, one of such ears being shown in full lines and the other in dotted lines. These ears are perforated in order to provide means for attaching the pull-off or span wires usually employed. The perforations in these ears 70 are located substantially in the same horizontal plane with the groove for the reception of the line conductor in order that the strain may be applied at the proper point and all danger of changing the position of the conductor with reference to the track avoided.

The ears 3 may be made of or coated with insulating material, or, if preferred, suitable insulating devices may be employed for attaching the pull-off wires thereto.

Where this device is employed at curves in connection with supporting means located at one side of the track only, it will be constructed with a single supporting-ear. Where the supports are located at both sides of the 85 track, both supporting-ears will be employed.

I claim as my invention—

1. A supporting device for electric-railway conductors consisting of a bar having a longitudinally-grooved upper edge and a curved 90 lower edge, and provided at one side, substantially midway of its ends with a perforated ear, the perforation in said ear and the groove in said bar being in substantially the same horizontal plane.

2. A pull-off device for electric-railway conductors consisting of a bar having a longitudinally-grooved upper edge and a curved 95

lower edge, and provided with a laterally-projecting perforated ear at each side, substantially midway of its ends, the perforations in said ears and the groove in said bar being in substantially the same horizontal plane.

5 In testimony whereof I have hereunto sub-

scribed my name this 14th day of September, A. D. 1896.

HARRY P. DAVIS.
